MOTOR-EQUIPPED SNOW PLOW

Henry J. Behrens, Melvin H. Bemis, Edward R. Greer, and Andrew E. Morrison, Minneapolis, Minn., assignors to Rotary Snow Plow Company, Minneapolis, Minn., a corporation of Minnesota

Application October 12, 1936, Serial No. 105,252

15 Claims. (Cl. 37—43)

This invention relates to a snow plow and particularly to a snow plow having one or more rotors which operate to discharge the snow moved to them.

5 It has been the common practice heretofore to propel the plows along the highway by an automotive vehicle and to drive the rotors from the motor of said automotive vehicle. In one well known type of plow this was done by a connection between the crank shaft of said motor and the driving shaft for said rotors.

With this method of both propelling the plow forward and driving the rotors by the same motor, serious difficulties have been encountered. 15 in order to properly discharge the snow it is desirable to have the rotors run at a constant speed or at least at a minimum speed. The snow, however, varies in weight and hardness and it is impossible to propel the plow at a uniform speed. 20 The snow is often packed very hard and the plow can only be progressed into the snow very slowly. One demand is therefore being made on the motor for high speed and another demand being made on the motor which causes the motor to 25 use a slow speed. This gives difficulty in getting the proper power with which to progress the plow and to operate the rotors. Difficulty is also experienced in getting enough power to take care of the required loads or work.

30 It is an object of this invention to provide a plow having one or more rotors, with one or more internal combustion motors carried by the plow which can be run at uniform speed to drive the rotor or rotors so that the plow may be progressed by the motor of the automotive vehicle, which latter motor is thus relieved of the rotor drive.

It is a further object of this invention to provide a snow plow having a pair of rotors for discharging snow, with one or more internal combustion motors provided only to drive the rotors, suitable connections being made between said motors and rotors.

It is still another object of the invention to 45 provide a snow plow having one or more internal combustion motors for driving the rotors and a novel and efficient construction of mounting for said motors.

It is another object of the invention to provide 50 a snow plow having a pair of rotors for discharging snow, with a pair of internal combustion motors, said motors having pinions meshing with a common gear for driving said rotors.

It is another object of the invention to provide 55 a snow plow having a pair of discharging rotors,

a shaft to which said rotors are secured, a second shaft connected to said shaft, a gear secured to said second shaft, a casing enclosing said shafts and gears and a pair of motors carried by said plow having casings secured to said 5 casing.

It is also an object of the invention to provide a novel and efficient structure of rotor for a snow plow.

These and other objects and advantages of the 10 invention will be fully set forth in the following description made in connection with the accompanying drawings, in which like reference characters refer to similar parts throughout the several views and in which:—

15 Fig. 1 is a view partly in plan and partly in horizontal section;

Fig. 2 is a view in side elevation of the plow, some parts being indicated in dotted lines;

Fig. 3 is a view in rear elevation of the plow, 20 some parts being broken away and others shown in vertical section;

Fig. 4 is a vertical section taken substantially on line 4—4 of Fig. 3 or Fig. 1 as indicated by the 25 arrow;

Fig. 5 is a view in side elevation of the rotor;

Fig. 6 is a central horizontal section of the rotor and driving shaft;

Fig. 7 is a view in end elevation of the central 30 part of the rotor, some parts being shown in vertical section;

Fig. 8 is a vertical section through the clutch portion of the motor and the drive therefrom;

Fig. 9 is a horizontal section mainly through the rotor shaft of a modified form of construction and partly above said shaft; and

Fig. 10 is a vertical section taken on line 10—10 35 of Fig. 9 as indicated by the arrows.

Referring to the drawings, a snow plow is shown comprising a central moldboard 10 which 40 is of the V type with a central forwardly directed point. The sides of moldboard 10 extend rearwardly to the open front ends of discharge chutes 11. Side plates or moldboards 12 are disposed at each side of the plow and extend rearwardly 45 and inwardly to the outer sides of the discharge chutes. The plates 12 have side plates 13 secured to the outer sides thereof having sharpened front edges. The moldboards are secured to a frame member 14 extending transversely of the plow 50 at the top of the moldboards, said member being illustrated as in the form of an angle bar. Plates 15a extend horizontally of the plow adjacent the bottom thereof at the outer sides of chutes 11 and a plate 15 extends horizontally between chutes 55

11 at the bottom thereof and some distance beyond the same. Pairs of lugs 15b project rearwardly from the outer moldboards 12 and are apertured to have connected thereto the push bars for propelling the plow. The chutes 11 have curved bottom portions 11a and extend upwardly, being rectangular at their upper ends. Brackets 16 are secured to the sides of the chutes and have pivoted thereto deflecting members or chutes 17. The chutes 17 may be swung on or about their pivots 18 to deflect the snow to one side or the other of the plow. Plates 19 are secured to the inner sides of chutes 11 and to the rear of the central moldboard and have bearing blocks 20 supported thereon. Bearing hubs 21 have rounded or curved annular portions resting in semi-cylindrical grooves in the top of blocks 20. Upper blocks 22 rest on top of the curved annular portions of hubs 21 and headed and nutted bolts 23 extend through blocks 20 and 22 and through the plates 19, thus securing said blocks in position. Upper blocks 22 also have semi-cylindrical grooves receiving hubs 21. The grooves in blocks 20 and 22 are also curved transversely or longitudinally of hubs 21 and on a longer radius than the annular curved portions of hubs 21 so that there would be some freedom for rocking movement. Hubs 21 have roller bearings 24 shown as of the Timken type therein and a shaft 25 is journaled in said bearings. Shaft 25 extends through and is secured to the hubs of rotor members 26. These rotor members are shown specifically in Figs. 5 to 6. Each comprises a central annular plate 30 illustrated as having a shoulder-forming bear 30a extending thereabout. A hub 31 has a flange 31a secured to one side of plate 30 and a hub 32 has a flange 32a secured to the opposite side of plate 30, said flanges being secured by a plurality of circumferentially spaced headed and nutted bolts 33 extending through said flanges and plate 30. The outer edges or peripheries of said flanges engage the shoulders formed by beads 30a. Hub 31 has an outer flange 31b and hub 32 has an outer flange 32b. A roller bearing 34 is disposed in hub 31 in which may run a reduced portion 25a of shaft 25. A plate 35 is disposed between the end of bearing 34 and the shoulder of shaft 25. A plate 36 is threaded on shaft 25 and engages the outer end of bearing 34. Beyond plate 36 shaft 25 has a splined portion 25b and a driving member 37 is bored and slotted to fit portion 25b so as to rotate with shaft 25. Member 37 has a plurality of radial slots or recesses 37a formed in its outer end and one or more frangible headed pins 38 extend through holes in hub 32 and into the recesses 37a. Hub 32 has outwardly projecting lugs 32c apertured to receive a split key 32d which holds the pin 38 in place. An end cap 39 has a semi-spherical end and also has a flange engaging the outer end of member 37 to which it is connected by the screws 40. The rotor comprises a plurality of blades or scoops 41, the same being trough-shaped or of concavo-convex form. Blades 41 are shown as formed of sheet metal plates, said plates being widest at their central portions and tapering toward their ends. The ends of said plates forming the sides of said blades or scoops are secured respectively to the inner sides of flanges 31b and 32b by and are swingable about the headed and nutted bolts 42. Plates 43 which are elongated and of general crescent form are disposed at either side of plate 30 and connected thereto by headed and nutted bolts 42c. Plate 30 is pro-

vided with additional holes 30b through which bolts 42c may extend with blades 41 in different positions. Blades 41 are provided at their ends adjacent the periphery of plate 30 with slots 41a to accommodate the swinging movement of said plates when they are adjusted to different positions. Plates 43 extend along and are connected to the rear or convex sides of the blades 41 in any suitable manner as by welding. As shown in Fig. 6 plates 43 diverge toward their outer ends. A bead or rod 44 of very hard metal is secured to the edge of blades 41 in any suitable manner as by welding.

A beveled gear 45 is secured to shaft 25 and meshes with another beveled gear 46, which latter gear is secured to a shaft 47 extending at right angles to shaft 25 and rearwardly of the plow. Hubs 21 form part of and are secured to a casing 48 which encloses shaft 25 and shaft 47 together with gears 45 and 46. The ends of hubs 21 are closed by plates 49. Casing 48 has a forward portion with a circumferential flange 48a to which is secured a cover plate 50 by the circumferentially spaced screws 51. Casing 48 has a rearwardly extending cylindrical portion 48b 25 extending to and communicating with an annular portion 48c having a projecting flange 48d. Portion 48c has projecting forwardly therefrom frusto-conical portions 48e, each of which has a peripheral flange 48f disposed in a plane at right 30 angles to the axis of shaft 47. Portions 48e have central hub portions each having a bore adapted to receive a bearing 52. A casing 53 has a flange 53a mating with flange 48d to which it is connected by a plurality of circumferentially spaced 35 screws 53f. Member 53 has bores therein axially aligned with said bores in portions 48c adapted to receive bearings 54. Member 53 also has an opening covered by a plate 53e. Shaft 47 is journaled in spaced bearings 47a disposed in casing 40 portion 48b and said shaft has secured thereto a comparatively large spur gear 55. A nut 55a is threaded on the end of shaft 47 holding gear 55 thereon. Gear 55 is disposed in a chamber formed by casings 48 and 53. The outer end of 45 casing 53 has a projecting horizontal lug 53d apertured to receive a stud 57 threaded at both ends and having a nut 58 threaded thereon engaging the lower side of lug 53d. Stud 57 extends through an aperture in a horizontal flange 50 of an angle bar 59 extending between and secured to the rear sides of chutes 11. A coiled compression spring 60 is disposed between lug 53d and the bottom of angle bar 59. A coiled compression spring 61 is disposed on top of bar 59 on the top 55 of which is disposed a washer 62. Stud 57 extends through the springs 60 and 61 and through washer 62 and has threaded on top of washer 62 a nut 63. With this construction it will be seen that the casings 53 and 48 are resiliently supported at the rear end by the springs 60 and 61.

A pair of motors 65 are provided and these motors are illustrated as and are preferably of the internal combustion type. While various motors might be used, in practice the motor of the modern Ford V8 truck has been used. Each motor has a rear end casing 65a which in the truck is adapted to be bolted to the end of the change speed gear casing. In the present invention casing 65a is bolted to flange 48f by the circumferentially spaced bolts 66.

Each motor 65 has an angle bracket 67 secured to the front of its crank case at each side, which brackets rest upon coiled compression springs 68. One spring 68 rests on top of a flange 50a extend- 75

ing at the top of cover plate 50. The other spring 68 rests on top of a flange 48g formed on casing 48. Coiled compression springs 70 rest respectively on each bracket 67 and are surmounted by washers 71. Headed and nutted bolts 69 extend through the springs 68 and 70 and through brackets 67 and washer 71, one of said bolts extending through flange 50a and the other through flange 48g, said bolts holding said springs and brackets in place. The bottom of the radiator casing 65b has an outwardly projecting flange 65c at each side which rests upon a coiled compression spring 72. One spring 72 rests on flange 50a and the other rests upon the front portion of flange 48g. Coiled compression springs 73 rest on top of flanges 65c respectively and are surmounted by washers 74. Headed and nutted bolts 75 extend through springs 72 and 73, through washer 74 and flanges 65c. One of said bolts extends through flange 50a and the other through flange 48g, said bolts acting to hold said springs and flange 65c in position. It will be seen that with this construction the front parts of the motors 65 are resiliently supported.

25 Motor 65 is shown rather diagrammatically in outline, the cooling fan 65d being shown and the water connections 65e and 65f which extend to the radiator. The pulley 65g which drives fan 65d is shown as well as another pulley 65h which 30 is provided to drive the governor 65i. The governor is provided to secure a constant speed for the motor. The governor may be any one of the well known commercial types and per se forms no part of the present invention.

35 The motor 65 has the usual fly wheel 80 secured to the crank shaft thereof, said flywheel having a surface engaged by the clutch plates 81 of the clutch used with the motor. This clutch will be used in the plow. Said clutch comprises 40 another annular member 82 adapted to engage the side of the clutch plates 81 opposite member 80. Member 82 has projecting lugs 82a to which are pivoted respectively the outer ends of levers 83. Levers 83 are pivoted intermediate their ends 45 to and are carried by an annular plate 84, having a flange 84a secured to flywheel 80. Plate 84 has recesses formed therein adapted to receive coiled compression springs 85, one end of each of which seats against plate 84 and the other end of which 50 seats against member 82, said latter member having projections 82b disposed within said springs. A member 86 is carried on and slidable on a shaft 87, which shaft has a splined end 87a fitting in a hub 81a to which clutch plates 81 are secured.

55 An annular plate 88 surrounds shaft 87 and member 86, the same being adapted to rotate against ball bearings 89 carried thereon and by member 86. Plate 88 is adapted to engage the ends of adjustable bolts or pins 90 carried in the inner ends 60 of levers 83. Member 86 is provided with projecting lugs 86a engaged by the forked end of a clutch operating lever 91 pivoted on a shaft 92 journaled in casing portion 48e. Shaft 92 is oscillated by a lever 93 secured thereto at the 65 outer side of casing portion 48e. Member 86 is moved to normal position or retracted by tensile coiled spring 94 secured thereto and to casing portion 48e. Shaft 87 is journaled in bearings 52 and 54. Each shaft 87 has a pinon 96 secured thereto between the bearings 52 and 54, which pinions mesh with gear 55.

In Figs. 9 and 10, a modified construction is shown which is used in plows where the rotor shaft is of considerable length and in which it 75 could not be put in place in one piece. A mold-

board 100 is shown quite similar in construction to moldboard 10 but which is used on a plow not having the outer moldboards 12. A central shaft 101 is used which is journaled in bearings 102 spaced longitudinally thereof and secured in a 5 casing 103 which takes the place of casing 48. A beveled gear 104 is secured to shaft 101 by a key 105 and meshes with another beveled gear 106 secured to a shaft 107 by a key 108. Shaft 107 is in all respects the same as shaft 47 already described and casing 103 has therein a bearing 109 for shaft 107. Bearing 109 corresponds to bearing 47a and casing 103 extending rearwardly from bearing 109 is in all respects identical with casing 48 already described. Casing 103 at its front 15 end is provided with a flange 103a and is closed by a plate 110 secured to flange 103a by the circumferentially spaced bolts 11. Casing 103 has lateral extensions 103b provided at their outer ends with flanges 103c. An elongated casing 112 20 has an enlarged end 112a which is connected to flange 103 by the circumferentially spaced bolts 113. There is, of course, one casing 112 at each side of casing 103 and casings 112 project through the sides of the moldboard 100. The end 112a 25 of casing 112 is, as shown, of enlarged form and has a rounded or partly spherical surface. This enlarged end is received in a split bearing, one-half of which 114 is disposed beneath the moldboard 100, engages the same at one side and is 30 welded thereto. In addition a plate 115 of general segmental form extends around the periphery of member 114 and is bent or warped so as to lie against the moldboard 100 and be welded thereto. Member 114 is provided with oppositely 35 projecting lugs 114a. Another one-half bearing 116 extends around the outer side of enlargement 112a and has projecting lugs 116a secured to lugs 114a by the bolts 117. It will be seen that there is provision for some movement of casing 40 112 in the bearing provided by members 114 and 116. The outer terminal ends of shaft 101 beyond bearings 102 are splined throughout their peripheries. Each of said ends extends into a splined sleeve 118 to which it is thus connected. 45 Shafts 119 have splined inner ends projecting respectively into the sleeves 118 and are thus connected to said sleeve to be driven by shaft 101. A sleeve 120 is disposed between bearing 102 and a collar 121 secured to the inner side of portion 50 112a of casing 112, said collar being secured by circumferentially spaced screws 122. A cylindrical sleeve 123 is secured in the outer end of casing 112 and projects beyond said end. Shaft 119 projects through and beyond casing 112 and 55 sleeve 123 and has an outer splined end fitting in the splined bore of a block 124. Block 124 is similar to member 27 already described and forms the driving member for the rotor, the central portion of which is shown as 125. Rotor hubs 126 and 127 are bolted to the opposite sides of portion 125 just as shown in Fig. 6. Hub 127 is driven from member 124 by frangible pins 128 extending through slots 124a in the outer flanged end of member 124. Pins 128 are the same as pins 60 129 and are similarly held by cotter pins or split keys 129 extending through spaced lugs 127a on member 127 which are similar to the lugs 32c already described. Hub 126 carries two longitudinally spaced bearings 130 just as does hub 65 member 31, a collar 131 being disposed between the inner bearing and the end of casing 112. Hub members 126 and 127 have flanges 126b and 127b similar to the flanges 31b and 32b to which the rotor blades will be connected as shown in 70 75

Fig. 6. As stated, casing 103 is similar at its rear end in all respects to casing 48 and will have the portions similar to portions 48e and flanges similar to flanges 48f to which the motors will be connected. Casing 103 will have extensions similar to extensions 48g, whose position is indicated by dotted lines 103d in Fig. 9. Plate 110 will have projecting flanges similar to the flange 50a on plate 50, the position of which is indicated as 110a. The lower part of the radiator casing similar to the flange 65c is indicated in dotted lines in Fig. 9. The positions of springs 69 and 72 are indicated in Fig. 9 as are the positions of springs 68 and 72.

15 From the description of the structure shown in Figs. 9 and 10 it is seen that the assembly can be quite easily made. The shafts 119 can be placed in position endwise. Shaft 101 is reversible if desired. It will also be seen that casing 103 can 20 rock about the axis of shaft 101 in the bearings 114 and 116 just as casing 48 can rock in the bearings formed by members 20 and 22. Casing 103 will be supported at its rear end by springs exactly as is casing 48 or casing 53 secured 25 thereto.

In operation, a plow will be propelled forwardly to clear the snow by an automotive vehicle, such as a truck or tractor, to which it will be connected by suitable push bars. The motor 30 of the automotive vehicle will thus furnish the propelling power. Motors 65 will be operated and when it is desired to operate the rotors, the operator will move lever 93 to engage the clutch and connect shafts 87 to the motor crank shaft. 35 Shafts 87 through the pinions 96 will drive gear 55 and shaft 47 will thus be driven. Shaft 25 and the rotors will be driven through gears 45 and 46. As stated, the motors 65 will be run at constant speed and the rotors 26 will thus be driven 40 at constant speed and will have ample power to discharge any snow moved thereto. The operator will thus not have to give any attention to the driving of the rotors. The plow can be advanced into the snow as rapidly as possible by 45 the motor of the automotive vehicle. The mounting of the motors insures that there will be no binding or twisting of shaft 87. It will be noted that the casing 48 which carries the motors is mounted with 3-point support. The same 50 is mounted on the bearing box 20 and has a central or intermediate mounting through lug 53d which is a yielding mounting. This yielding mounting will give opportunity for some adjustment between shaft 25 and the casing 48 so that 55 there will be no binding. It will be noted that the casing 48 is movable about the axis of shaft 25 in one direction and is controlled in this movement by the spring mounting comprising springs 60 and 61. It will be understood that the 60 snow is moved rearwardly and laterally by the moldboards 10 and 12 into the chutes 11. As shown in Fig. 2 the front lower part of the chutes is substantially in vertical alinement with the axis of the rotors and the ends of the blades 65 or scoops 41 pass rather close to the bottom of the chutes. As the rotors revolve they propel the snow upwardly through chutes 11 and it is discharged to one side or the other by the deflectors 17. The rotors are of simple, rugged and efficient 70 construction and particularly designed for very heavy duty. The plow frequently encounters large pieces of ice and boulders which are hidden by the snow and these must be discharged by the rotors. Large pieces are broken up by the 75 rotors before passing out through the chutes.

Should the rotors strike some very heavy or rigid object the pin or pins 38 will be sheared and the shaft 25 will then run idly in the bearing 34. The rotor can then later be reattached to the shaft by a new pin or pins 38.

With the construction shown in Figs. 9 and 10 the rotors are driven from gear 55 through shaft 107, gears 104 and 106 and through shafts 101 and 119. Should the shear pins 128 break the rotor will run idly on the bearings 130 carried on 10 sleeve 123.

From the above description it is seen that applicants have provided a novel, simple and very efficient construction of snow plow. The plow will have ample power for the intended duty and 15 the rotors can be driven at constant speed regardless of the power used to push the plow into a drift or hard tract of snow. The motors for driving the rotors are as described mounted directly on the plow and a novel, efficient and flexible mounting is provided for them. The parts have been amply demonstrated in actual practice and found to be very successful and efficient.

It will, of course, be understood that various changes may be made in the form, details, arrangement and proportions of the parts, without departing from the scope of applicants' invention, which generally stated, consists in a device capable of carrying out the objects above set forth in the parts and combinations of parts disclosed and defined in the appended claims.

What is claimed is:

1. A snow plow adapted to be propelled by an automotive vehicle having in combination, a frame, rotors for discharging snow disposed at either side thereof, means for moving snow to said rotors, a shaft extending between said rotors on which said rotors are mounted, driving means for said shaft, a casing for said last mentioned means, a pair of internal combustion motors rigidly secured to said casing, resilient means also supporting said motors and a second driving means secured to said motors for driving said first mentioned driving means.

2. A snow plow adapted to be propelled by an automotive vehicle having in combination, a frame, a moldboard secured to said frame, rotors for discharging snow mounted on said frame to which snow is moved by said moldboards, a shaft on which said rotors are mounted, a second shaft for driving said shaft, an internal combustion motor, means on said frame on which said motor is movably mounted, resilient means also supporting said motor and gearing connecting said second shaft and motor for driving said shafts and rotors.

3. A snow plow adapted to be propelled by an automotive vehicle having in combination, a frame, spaced rotors for discharging snow, means for moving snow to said rotors, means extending between said rotors on which said rotors are mounted, a casing enclosing said means, a pair of internal combustion motors each rigidly secured at one end to said casing and resilient means on said casing for supporting said motors at their other ends.

4. A snow plow adapted to be propelled by an automotive vehicle having in combination, a frame, a pair of rotors for discharging snow, a shaft coaxial with said rotors for driving the same, a pair of internal combustion motors for driving said shaft and a movable member for supporting said motors having a three-point support on said frame.

5. A snow plow adapted to be propelled by an

automotive vehicle having in combination, a frame, a pair of rotors for discharging snow, means for moving snow to said rotors, a shaft extending between said rotors to which said rotors are secured, a second shaft for driving said first mentioned shaft extending at right angles thereto, a gear secured to said second shaft, a casing enclosing said second shaft and said gear having circular flanges thereon, a pair of internal combustion motors having casings secured respectively at one end to said flanges each of said motors having a crank shaft, a pair of shafts alined respectively with said crank shafts and driven thereby each having a pinion thereon meshing with said last mentioned gear and a clutch for connecting and disconnecting each of said shafts and the respective motors of said pair.

6. A snow plow adapted to be propelled by an automotive vehicle having in combination, a frame, a rotor for discharging snow, means for moving snow to said rotor, a shaft on which said rotor is mounted, a casing for said shaft having a circular flange thereon, an internal combustion motor having a casing rigidly secured at one end 20 to said flange, resilient means spaced from said flange also supporting said motor, a shaft driven by said motor and gears connecting said last mentioned shaft and first mentioned shaft.

7. A snow plow adapted to be propelled by an automotive vehicle having in combination, a frame, a rotor for discharging snow, means for moving snow to said rotor, a shaft for driving said rotor, a gear secured to said shaft, a pinion meshing with said gear, a casing enclosing said shaft, pinion and gear having a circular flange thereon, an internal combustion motor having a casing secured at one end to said flange, a shaft parallel to said shaft driven by said motor for driving said pinion, means for connecting and disconnecting said motor and last mentioned shaft, said first mentioned casing being carried on said frame and movably supported at one end.

8. A snow plow adapted to be propelled by an automotive vehicle having in combination, a frame having supports thereon, a rotor for discharging snow, a shaft for driving said rotor, a casing for said shaft, an internal combustion motor rigidly secured to said casing, said casing being movably mounted on said supports on said frame, resilient means spaced from said supports for holding said casing in position and means for driving said shaft from said motor.

9. A snow plow adapted to be propelled by an automotive vehicle having in combination, a frame, a rotor for discharging snow, means for moving snow to said rotor, an internal combustion motor having a crank shaft, a member movably mounted on said frame to which said motor is secured and an additional resilient mounting 60 for said member.

10. A snow plow adapted to be propelled by an automotive vehicle having in combination, a frame, a rotor for discharging snow, means for moving snow to said rotor, an internal combustion motor movably mounted at one portion on said frame, and resiliently mounted at another portion and means for driving said rotor from said motor.

11. A snow plow adapted to be propelled by an automotive vehicle having in combination, a frame, rotors for discharging snow carried thereon, means for moving snow to said rotors secured to said frame, a shaft extending between said rotors on which the same are mounted, a casing enclosing said shaft, a pair of motors supported on said casing, said casing being supported at spaced points on said frame and resilient means supporting said casing at a third point on said frame. 10

12. A snow plow adapted to be propelled by an automotive vehicle having in combination, a frame, a rotor mounted on said frame for distributing snow, a moldboard secured to said frame for moving snow to said rotor, a shaft on 15 which said rotor is mounted, a gear for driving said shaft, a pinion meshing with said gear, a second shaft to which said pinion is secured, a casing enclosing said pinion and gear, an internal combustion motor secured at one end to said 20 casing and having a crank shaft parallel to said second shaft, means for connecting and disconnecting said second shaft and said crank shaft means on said frame on which said motor is movably supported and resilient means for additionally supporting said motor. 25

13. A snow plow adapted to be propelled by an automotive vehicle having in combination, a frame, spaced rotors mounted on said frame for discharging snow, means secured to said frame 30 for moving snow to said motors, a shaft for driving said rotors, a gear secured to said shaft, a pinion meshing with said gear, a casing enclosing said shaft, gear, and pinion and having attaching means thereon at each side of said shaft, a pair of internal combustion motors having casings secured at one end respectively to said attaching means and thus disposed respectively at either side of said shaft, means for movably supporting said motors between their ends and resilient means for supporting said motors at their other ends. 35

14. A snow plow adapted to be propelled by an automotive vehicle having in combination, a frame, a rotor supported on said frame for discharging snow, means secured to said frame for moving snow to said rotor, a shaft for driving said rotor, a motor for driving said shaft, a member to which said motor is secured, said member being mounted for swinging movement 40 and resilient means for limiting said movement. 50

15. A snow plow having in combination, a frame, means connected to said frame adapted to be engaged by an automotive vehicle for propelling said plow, spaced rotors for discharging snow, said rotors being rotatable about a common axis, a shaft disposed between said rotors and extending at an angle to said axis for driving said rotors, a motor disposed at each side of said shaft, driving means driven by each motor for driving said shaft and a casing movably and resiliently mounted on said frame on which said shaft and rotors are mounted and to which said motors are secured. 60
